COMBINATION BED

John Pejka, Detroit, Mich.

Application May 14, 1942, Serial No. 442,881

1 Claim. (Cl. 5—330)

My invention relates to a new and useful improvement in a bed, and has for its object the provision in a bed of separating partition which may be easily and quickly placed in position to separate occupants of the bed and render them some privacy while at the same time it may be easily and quickly removed.

Another object of the invention is the provision of a head shield which is swingably mounted between a pair of cabinets which are supported on a bed so that when the shield is swung to inoperative position, no obstruction is offered to a person sitting on the bed and using the cabinet.

Another object of the invention is the provision in combination with a bed of a pair of separated cabinets supported on a bed and provided with mirrors which may be swung downwardly for position of use and swung upwardly out of operative position so as to protect the glass thereof.

Another object of the invention is the provision in a bed of separating sectional partition so arranged so that it may be easily and quickly fastened in position.

Other objects will appear hereinafter.

It is recognized that various modifications and changes may be made in the structure illustrated without departing from the spirit of the invention, and it is intended that such variations and departures shall be brought within the scope of the claims forming a part hereof.

Forming a part of this specification is a drawing in which,

Fig. 1 is a top plan view of the invention.

Fig. 2 is a side elevational view of the invention.

Fig. 3 is a sectional view taken on line 3—3 of Fig. 1.

Fig. 4 is a sectional view taken on line 4—4 of Fig. 1.

Fig. 5 is a fragmentary, sectional view illustrating the rod connection used in the invention.

Fig. 6 is a fragmentary, sectional view with parts broken away and parts shown in side elevation of the partition used in the invention.

In the drawing, I have illustrated a bed comprising the bed posts 9 and 10 which support a mattress 11 in the usual manner. Mounted on the bedpost or bedstead 10 is a pair of cabinets 12, each having a plurality of drawers 13 and each provided with a swingable plate 14 having a mirror on its inner face so that when the plate 14 is swung to closed position the glass will be protected. When swung downwardly as shown in

Fig. 4, a person sitting on the bed may use the mirrors as a dresser and the drawers of the cabinets 12 will be readily available.

5 Mounted on the bedstead 9 is a bracket 15 to which is attached, by the pin 16, one end of a sectional rod 17. One section is attachable to rod 18 extending outwardly from a head partition 19 which is swingably mounted by the arms 20 to the bedstead 10. When swung downwardly, 10 into the position shown in Fig. 1 and Fig. 2, the sectional rod and the shield 19 will serve as a separating element for separating persons lying on the bed. The shield 19 will shield the face or heads of the persons from each other so that 15 some privacy is thus afforded and so that one person will not be breathing in the face of the other.

When the sectional rod is detached, the shield 19 may be swung upwardly as shown in dotted 20 lines in Fig. 2, so as to lie between the cabinets 12 and thus offer no obstacle to the persons lying on the mattress 11.

25 The shield 19 carries on a pin 21 which serves as a stop and which is adapted to bear against the bedstead 10 so as to limit the downward swinging of the shield 19.

With a bed so constructed, a maximum convenience and comfort is afforded to the persons occupying the same and a structure is provided 30 which is quite practical where limited facilities are present. Particularly is this so where the room is not fitted with a dresser, such as is the case in lake cottages, hunting cabins, and the like.

35 In this manner, I have provided a combination bed combining a bed, a protective shield or separating member and the equivalent of a dresser with drawers.

What I claim as new is:

40 In combination with a bed having a mattress and a bedstead having a portion projecting upwardly from one end thereof, a partition-forming member; a pair of arms connected on opposite sides of said member and projecting outwardly therefrom, at opposite sides thereof and swingably connecting said member to said bedstead portion for swinging downwardly in to engagement with a mass and upwardly out of engagement therewith for, when swung to operative position, shielding the heads of adjacent persons lying in the bed; and an abutment pin carried by said partition-forming member and engageable with the bedstead portion for limiting downward swinging of said member.

JOHN PEJKA.
